NONREFILLABLE BOTTLE

Mario J. Belgeri and Theodore F. A. Unland,
St. Louis, Mo.

Application August 6, 1934, Serial No. 738,606

2 Claims. (Cl. 215—30)

This invention relates to non-refillable bottles.

The main object of the invention is to provide a bottle of novel construction, that cannot be refilled or used more than once as a container for liquid that is sold to the public.

Another object of the invention is to provide a bottle, which, in addition to having the desirable characteristic or feature above referred to, is of such design or construction that the contents of the bottle can be easily poured from the bottle.

Briefly described, our invention consists of a bottle comprising a lower portion that holds the liquid to be dispensed, an upper portion provided with a neck or spout, and a hemispherical-shaped sealing chamber in said upper portion, connected with the lower portion of the bottle by one or more ports or ducts that lead from the peripheral edge of said sealing chamber at a point above the central portion of the concaved bottom of said chamber, and connected with said spout or neck by a passageway that leads upwardly from the center of said sealing chamber. Due to the fact that said sealing chamber is substantially dished or bowl-shaped, and is connected with the spout by a passageway that leads upwardly from the depressed central portion of said chamber, the part of the upper portion of the bottle that forms the top wall of said sealing chamber constitutes a depending, annular-shaped baffle whose lower end terminates at a point below the upper end of the duct or ducts previously mentioned, that lead downwardly from the peripheral edge of the sealing chamber and establish communication between said chamber and the lower portion of the bottle that holds the liquid to be dispensed. Consequently, if liquid be poured into the spout in an attempt to refill the bottle, such liquid, even if it should find its way into the sealing chamber, will rise in said chamber and submerge the lower end of said baffle, thus producing an air lock in the upper portion of the sealing chamber which prevents said liquid from rising high enough to overflow or escape from the sealing chamber through the duct or ducts that lead downwardly from the peripheral edge of the sealing chamber, and which constitute the sole outlet from said chamber to the lower portion of the bottle. In other words, in our improved bottle there is a sealing chamber in the upper portion of the bottle, provided with a concaved bottom arranged in direct longitudinal alignment with

the spout and overhung by an annular baffle disposed so that any liquid which might pass inwardly through the spout or the passageway that extends from the spout to the sealing chamber, would collect in the central portion 5 of the sealing chamber, and upon rising in said chamber, would submerge the lower end of said baffle, and thus form an air lock in the upper peripheral portion of the sealing chamber that would effectively prevent liquid from 10 escaping from the sealing chamber into the lower portion of the bottle, through the duct or ducts at the peripheral edge of the sealing chamber.

If desired, the upper portion of the bottle that contains the sealing chamber may be formed as one unit, and the lower portion of the bottle may be formed as a separate unit that has no top, the lower portion of the bottle being adapted to be filled with liquid and thereafter closed by combining or attaching said lower portion with the upper portion in such a manner that said portions cannot thereafter be separated or detached without breaking one or the other of said portions, or making it clearly apparent to the public that the bottle has been tampered with.

Figure 1 of the drawing is a vertical longitudinal view of our improved bottle.

Figure 2 is a horizontal sectional view, taken on approximately line 2—2 of Figure 1, looking in the direction indicated by the arrow.

Figure 3 is a horizontal sectional view, taken on approximately the line 3—3 of Figure 1, looking in the direction indicated by the arrow; 35 and

Figure 4 is a horizontal sectional view, taken on approximately the line 4—4 of Figure 1, looking in the direction indicated by the arrow.

As stated previously, we prefer to construct 40 the bottle in the form of two separate units or portions, to wit, a lower portion that serves as a container for the liquid to be dispensed and which is not provided with a top, and an upper portion that serves as a top for said lower portion and which is provided with a neck or spout and a sealing chamber, said units being connected together after the lower unit has been filled with the liquid to be dispensed. However, 45 we wish it to be understood that certain features of our invention, such as the sealing chamber and elements associated with same, are applicable to bottles in which the lower portion of the bottle is integrally attached to 50 55

the part of the bottle in which the sealing chamber is formed.

In the accompanying drawing which illustrates the preferred form of our invention, 9 designates the bottom unit or lower portion of the bottle that is adapted to serve as a container for liquid, and A designates the top unit or upper portion of the bottle that is combined with or attached to said lower portion 9 after said lower portion 10 has been filled. As shown in Figure 1, the bottom unit 9 consists of an open glass container provided with a bottom and with a side wall whose top edge terminates at a point above the liquid level. The particular means that is used 15 to connect or attach said two portions is immaterial and may be varied without departing from the spirit of our invention. In the form of our invention herein illustrated one of said units, for example, the lower portion 9 of the bottle, is provided at its upper end with a plurality of substantially cam-shaped ribs or lugs 7 that are adapted to be interlocked or arranged in engagement with co-operating grooves 10 in the top unit A, after which one of said units is rotated 20 in a direction to cause said lugs and grooves to co-operate with each other to draw said units together and compress a gasket 11 that is employed to produce a liquid-tight joint between said units. In order to prevent the units 9 and 25 A from being thereafter separated, the lugs 7 are equipped with resilient locking devices formed preferably by leaf springs 8 imbedded in the lugs 7 and arranged so that in the operation of turning or rotating said units to draw them together, as previously explained, the free ends of the locking devices 8 will snap into engagement with stops or shoulders 8^a on the top unit A, and thus effectively prevent said units from 30 being turned in the reverse direction so as to 35 disengage the lugs 7 from the grooves 10.

The upper portion A of the bottle is provided with a spout, neck or discharge portion 1, and said upper portion is also equipped with a sealing chamber 5, which is of such shape and arrangement 40 that when the chamber 5 contains liquid, air will be confined in said chamber in such a manner as to produce an air lock that effectively prevents liquid from being introduced into the bottle through the neck 1 to refill or replenish 45 the lower portion 9 of the bottle. As shown in Figure 1, the sealing chamber 5 is of substantially hemispherical shape or form and is disposed horizontally in the top portion A of the bottle in concentric relation with the spout 1, the concaved or dish shaped bottom of said 50 chamber being arranged below and in direct longitudinal alignment with the spout of the bottle. A plurality of open-ended, vertically-disposed ducts 6 are formed in the top portion 55 A so as to establish communication between the lower portion 9 of the bottle and the peripheral upper portion of the sealing chamber A. A valve chamber or vent chamber 3 is formed in the upper portion A of the bottle between the 60 spout 1 and the center portion of the sealing chamber 5, and a valve 4 is provided for normally cutting off communication between the sealing chamber 5 and the vent chamber 3. In the bottle herein illustrated the valve chamber 65 or vent chamber 3 is disposed vertically and provided with a tapered or inclined side wall whose lower end acts as a seat for a ball valve 4, said valve chamber 3 being of such shape and dimensions that when the bottle is tilted or arranged 70 in an inclined position to discharge liquid from 75

the spout 1 of the bottle, the valve 4 will unseat or roll towards the large end of the valve chamber 3, and thus vent the sealing chamber 5 and the lower portion 9 of the bottle in which the liquid is confined. If desired, a horizontally-disposed partition provided with orifices 2 may be arranged between the spout 1 and the valve chamber 3, so as to eliminate, or tend to eliminate, the possibility of the valve 4 being unseated by means of a wire or other instrument introduced through the spout 1.

At the center of the sealing chamber 5 is a depending baffle 5^a whose lower end terminates in a lower horizontal plane than the upper end of the ducts 6, previously mentioned. Consequently, in the normal use of the bottle, i. e., when small quantities of liquid are poured out of the bottle from time to time, a sufficient body of liquid will collect in the lower portion or central portion of the sealing chamber 5 to cover the lower end of the baffle 5^a, such confined liquid co-operating with said baffle 5^a to produce a liquid seal which cuts off communication between the spout 1 of the bottle and the upper portion of the sealing chamber 5 to which the ducts 6 lead from the lower portion 9 of the bottle. Similarly, if the bottle has been emptied and an attempt is made to refill the bottle by unseating the valve 4 and introducing liquid through the spout 1, the liquid which enters the sealing chamber 5 will rise in same and cover the lower end of the baffle 5^a, thereby trapping air in the upper portion of the chamber 5 and in the lower portion 9 of the bottle. It is practically impossible, however, for sufficient liquid to be introduced 35 into the sealing chamber 5 through the spout 1 of the bottle to cause such liquid to overflow through the ducts 6, due to the fact that the air which is trapped in the upper portion of the sealing chamber 5 when the lower end of the baffle 5^a is submerged in liquid, acts as an air lock to prevent liquid from rising in the sealing chamber 5 high enough to overflow or escape from said sealing chamber through the ducts 6. It will thus be seen that in our improved bottle 45 it is impossible to add liquid to the bottle or to refill the bottle through the spout 1, due to the fact that the sealing chamber 5 is of such shape and arrangement that when the baffle 5^a is submerged or partially covered by liquid in the sealing chamber 5, sufficient air is trapped in the upper portion of the sealing chamber 5 or in the lower part 9 of the bottle to resist a rise in the level of the liquid in the sealing chamber 5 to a height sufficient to permit such liquid to overflow 55 into the ducts 6. While the valve 4 is not absolutely essential, we prefer to equip the bottle with such a valve and also with a perforated baffle arranged between the spout and the valve chamber, as such elements further reduce the 60 possibility of the bottle being refilled or replenished.

The shape, dimensions and arrangement of the sealing chamber 5, the perforated baffle in the discharge passage and the ducts 6 may be 65 varied so long as said parts are of such design that the outlet from the sealing chamber 5 to the spout 1 is arranged in such relationship with the inlet to the sealing chamber 5 from the lower portion of the bottle, that a body of 70 air will be trapped in the sealing chamber 5, and thus constitute an air lock whenever the sealing chamber 5 contains sufficient liquid to cover or partially cover the baffle 5^a at the center of the sealing chamber. Preferably, the ducts 6 are 75

- located some distance inwardly from the outer edge of the sealing chamber 5, and an annular groove 12 is located at the extreme outer edge of the sealing chamber, as shown in Figure 1, 5 so as to tend to prevent a wire or small pliable tube from being fished into the lower portion 9 of the bottle, in an endeavor to replenish or refill the bottle through the spout 1. The two portions A and 9 of the bottle are preferably 10 made of glass, and the top portion A, in turn, is preferably made of two sections, which, after being molded, are joined or fused together on a line approximately coincident with the upper enlarged end of the valve chamber 3 after the 15 valve 4 has been introduced into said chamber.
- Having thus described our invention, what we claim as new and desire to secure by Letters Patent is:
1. A non-refillable bottle, comprising a lower portion adapted to act as a container for liquid and having no top, an upper portion constituting a top or closure for said lower portion and provided with a spout, co-acting means on said upper and lower portions for joining the same 20 together after said lower portion has been filled, a locking means which prevents said portions from being detached or separated without defacing one of said portions, a substantially hemispherical-shaped sealing chamber in said 25 upper portion arranged below said spout with the concaved bottom of said chamber in longitudinal alignment with said spout, ducts leading from the peripheral edge portion of said sealing chamber to the lower portion of the bottle, a means at the center of the sealing chamber which is adapted to co-act with liquid in said chamber to produce a liquid seal for the lower portion of the bottle, a vent chamber arranged between the sealing chamber and the spout of 10 the bottle, and a ball valve in said vent chamber for cutting off communication between said vent chamber and the sealing chamber when the bottle is in other than pouring position.
  2. A non-refillable bottle, comprising a spout 15 or discharge portion, a lower portion adapted to act as a container for liquid, a sealing chamber arranged in direct longitudinal alignment with the spout and having its peripheral portion connected by a duct with the lower portion of the 20 bottle, and a baffle that is adapted to co-act with liquid in said chamber to constitute an air lock which prevents liquid from passing from the sealing chamber into the lower portion of the bottle through said duct, the upper end of 25 said duct terminating in a horizontal plane higher than the lower end of said baffle.
